UNITED STATES PATENT OFFICE

FRANK DIETERLE, OF PHILADELPHIA, PENNSYLVANIA, ASSIGNOR TO GEORGE A. REACH, OF PHILADELPHIA, PENNSYLVANIA

BOXING GLOVE

Application filed December 1, 1928. Serial No. 323,037.

The invention is designed to provide a thumb construction which will contribute to a natural position of the user's thumb when the hand is clenched for boxing; which will be more durable than is possible with prior forms of thumb construction and which will give maximum protection to the thumb of the boxer.

Other objects of the invention will be obvious from the following description and the appended claim.

The invention is shown in the accompanying drawings in which:

Fig. 1 is a view of the glove from the palm side.

Fig. 2 is an enlarged sectional view taken longitudinally of the thumb of the glove, with the boxer's thumb in place.

Fig. 3 is an enlarged view showing the glove in the position it assumes when the hand of the boxer is clenched as in the act of boxing, the thumb portion being broken away and partly shown in section to make visible the position of the boxer's thumb.

Fig. 4 is a detail view.

The thumb of the glove is made up of the bag portion 1 and the palm portion 2, each, as usual, composed of leather. The leather of the bag portion 1 is carried around at 3 to the palm side of the palm portion 2 of the thumb and is stitched to the latter at 4, a considerable distance, say, for instance, one inch back from the terminal edge 5 of the palm section 2 of the thumb. This distance, i. e., the distance of the line of stitching 4 from the end 5 of the palm section of the glove is approximately equal to the length of the first joint of the thumb, so that the break (at 4) in the configuration of the palm thumb 20 coincides with and lies under the point of juncture *a* of the first and second joints of the thumb. The portion 3 of the bag thumb leather 1 which is extended back over the terminal portion *b* of the palm thumb leather 2 is spaced apart from the said terminal portion and into the space thus provided the hair stuffing *c* of the thumb is carried, so as to provide a layer of said stuffing at *d* directly opposite the end of the thumb and also at *e* 45 so that the latter body of the stuffing lies be-

tween the extension *b* of the palm thumb 2 and the overlapping extension 3 of the leather covering 1 of the bag portion of the thumb.

A lining of textile fabric 6 is stitched to the extreme end 5 of the palm thumb section 2 of the leather covering and it, together with the leather 2 and its extension *b*, forms a pocket or receptacle for the user's thumb.

From this construction it will be observed that the thumb of the boxer has two layers of leather on the palm side thereof, i. e., 3 and *b*, with the stuffing *c* interposed between said layers. This extension *b* serves as a reinforce for the layer 3 of the covering and prevents deterioration of the latter. Ordinarily the perspiration will cause deterioration of the leather on the palm side of the glove thumb and the boxer's thumb eventually will break through at this point. In my improved construction the bag thumb 1 being carried around at 3 forms in effect a part of the palm thumb and this will be protected by the extension *b* of the palm thumb 2, increasing the life of the latter not only by making a double layer of leather at this region, but also because it will prevent perspiration from the thumb reaching the layer of leather at 3 and, furthermore, the interposed stuffing *c* will provide ventilation.

Therefore the thumb of the boxer will not punch through the thumb of the glove. The construction described also protects the end of the boxer's thumb because the stuffing is carried around the end of the thumb at *d*, where it joins with the stuffing at *c*, which also aids in cushioning the thumb. It will be further noticed that the bag thumb portion 3 joins the palm thumb at an angle at the line of stitches 4 and this joint is directly adjacent the joint *a* of the user's thumb, so that the boxer's thumb may assume a natural bent position when the hand is clenched for boxing. The end of the thumb of the glove will to a degree embed itself in the mitt portion of the glove, as shown at *x* in Fig. 3, so that the boxer's thumb will be protected against being struck on the end, which might result in dislocation.

With my improvement the boxer's thumb

does not go to the extreme end of the thumb of the glove, nor does the end of the boxer's thumb go to the point where the line of stitches ordinarily join the bag thumb with the palm thumb, but with my improvement the boxer's thumb overlies this joint at 4, and is directed towards the intact portion of the bag thumb 1—3 and with the hair stuffing surrounding the end of the boxer's thumb.

10 I have shown in dotted lines in Fig. 1 the tongue or extension *b* and the lining 6 and this tongue is also indicated in dotted lines in Fig. 4. The lining is stitched to this tongue around the edge of the latter and also along the portions *x*—*y* and *x'*—*y'* of the seam between the palm thumb and bag thumb.

20 This virtually forms a stall for the end of the thumb made up of the tongue *b* and the lining, this stall lying within the mass of stuffing.

I claim:

25 A boxing glove having a thumb in which there is a double layer of leather at the palm side thereof and near the end thereof, said double layer continuing around the end of the thumb with hair stuffing between the layers, said double leather layer being provided by carrying the bag thumb in an unbroken layer around the end of the palm thumb and along the palm side of the thumb, and stitching the said bag thumb to the palm thumb at a point removed from the extreme end of the latter, said palm thumb likewise extending in an unbroken layer across the point of juncture of the bag thumb therewith.

30 In testimony whereof, I affix my signature.

40

FRANK DIETERLE.
